BOTTLE CARRYING BOX

Edward W. Hutchings, Perry, Fla.

Application April 30, 1942, Serial No. 441,161

4 Claims. (Cl. 217—19)

This invention relates to boxes or crates and more particularly to a box or crate especially designed for vending and transporting soft drinks and other beverages in bottles or similar containers.

The object of the invention is to provide a bottle carrier or box of simple and durable construction having a plurality of bottle receiving compartments therein and provided with a slotted bottom communicating therewith to permit the circulation of air through said compartments and thus insure proper ventilation and sanitation.

A further object is to provide a bottle carrying box or crate, the lower edges of the end walls of which are cut away or rabbeted to form seats for the ends of the spaced longitudinal strips constituting the bottom of the box, whereby the outer faces of said strips will be flush with the lower edge of the box and thus prevent the ends of said strips from coming in contact with an obstruction and becoming accidentally detached during transportation or shipment.

A further object is to reinforce and strengthen the end walls of the box by the provision of metal bands or straps which also serve to protect and retain the adjacent ends of the spaced longitudinal strips within the rabbeted seats and assist in holding the bottle receiving grill against vertical displacement.

A still further object of the invention is generally to improve this class of devices so as to increase their utility, durability and efficiency, as well as reduce the cost of manufacture.

In the accompanying drawing:

Figure 1 is a perspective view of a bottle carrying box or crate embodying the present invention.

Figure 2 is a longitudinal sectional view.

Figure 3 is a transverse sectional view on the line 3—3 of Figure 2.

Figure 4 is a top plan view.

Figure 5 is a detail perspective view partly in section, of one portion of the crate.

The improved bottle carrier or box forming the subject matter of the present invention comprises a relatively shallow body portion, preferably rectangular in shape and including vertical side walls 5 connected by end walls 6, said walls having their inner faces formed with vertical grooves 7 opening through the upper edges thereof as shown.

The lower edges of the end walls 6, at the confronting faces thereof, are cut away or rabbeted at 8, to provide seats for the adjacent ends of

longitudinal strips 9 constituting the bottom of the box or crate. The strips 9 are spaced apart to form intermediate ventilating openings 10 to allow free circulation of air through the box and also to permit drainage, thereby insuring proper ventilation and sanitation at all times.

Disposed within the box is a grill formed of a plurality of intersecting partitions 11 defining compartments for the reception of bottles and the like, the ends of said partitions fitting within the vertical grooves 7 with their lower edges resting on the spaced strips 9, as best shown in Figure 2 of the drawing.

The compartment forming grill is insertable as a unit within the box or crate from the top thereof and is held against vertical displacement by means of metal reinforcing bands or straps 12, the intermediate portions of which extend across the lower edges of the end walls 6 at the rabbeted portions thereof while the opposite ends of the straps extend upwardly over the side walls and thence over the top edges of the end walls and bear against the upper edges of the adjacent partitions constituting the grill. The reinforcing straps are secured to the box by nails or similar fastening devices 13, certain of which also extend through the ends of the longitudinal strips 9, thereby to firmly hold said strips to their seats. It will here be noted that the depth of the cut away portions or rabbets 8 is substantially equal to the thickness of the strips 9 so that, when the strips are in position within the rabbets to form the bottom of the box, the outer faces of said strips will be disposed flush with the lower edges of the side end walls of the box, thereby to present a smooth surface and prevent said strips from coming in contact with an obstruction and becoming accidentally detached from the end walls during transportation or shipment. It will thus be seen that the bands or straps 12 perform a three-fold function. First, to reinforce and strengthen the box, second, to hold the ends of the longitudinal strips 9 within their seats, and third, to prevent vertical displacement of the bottle receiving grill.

The end walls 6 are preferably formed with hand openings 14 to facilitate carrying the box and the partitions 11 adjacent said openings 14 are preferably cut away, as indicated at 15, to accommodate the fingers of the user and enable said user to obtain a firm grip on the box when carrying the same.

The vertical grooves 9 preferably intersect the seats or rabbets 8, as best shown in Figure 5 of the drawing.

It will thus be seen that there is provided a strong, durable bottle carrying box which may be conveniently handled and in which provision is made for ventilating the bottle receiving compartments and to permit drainage when necessary. It will, of course, be understood that the bottle carriers may be made in different sizes and shapes and constructed of any suitable material without departing from the spirit of the invention.

Having thus described the invention, what is claimed is:

1. A bottle carrying box comprising a body portion including connected side and end walls, the lower edges of the end walls at the confronting faces thereof being rabbeted to form seats approximately one half the thickness of said end walls and extending the entire length thereof, spaced longitudinal strips constituting the bottom of the box and having their opposite ends fitted in said seats, a compartment forming grill resting on said longitudinal strips, and reinforcing straps extending around the end walls and bearing against the ends of the strips and the upper portion of the grill for securing said ends within the seats and holding the grill in contact with the longitudinal strips.

2. A bottle carrying box comprising a body portion including connected side and end walls having their inner faces provided with vertical grooves, the lower edges of the end walls at the confronting faces thereof being rabbeted to form seats approximately one half the thickness of the end walls and extending the entire length thereof, spaced longitudinal strips constituting the bottom of the box and having their opposite ends fitted in said seats, a compartment forming grill resting on the longitudinal strips and formed of intersecting partitions fitting within the adjacent vertical grooves, and reinforcing straps having their intermediate portions extending across and in contact with the bottom edges of the end walls and overlapping and bearing against the adjacent ends of the strips at said seats for holding the strips within the seats, the opposite ends of the straps being extended over the upper edges of the end walls and in contact with the adjacent partitions for locking the grill in contact with said longitudinal strips.

3. A bottle carrying box comprising a body portion including side and end walls having their inner faces formed with vertical grooves, the lower edges of the end walls at the confronting faces thereof being rabbeted to form seats approximately one half the thickness of said end walls and extending the entire length thereof, spaced longitudinal strips constituting the bottom of the box and having their opposite ends of approximately the same thickness as the height of the seats and fitting therein, a compartment forming grill including intersecting partitions having their ends fitted within the vertical grooves and their lower edges resting on said strips, the outer faces of said strips being disposed flush with the lower edges of the side and end walls of the box, and reinforcing straps fitted around the end walls and having their intermediate portions extending across the lower edges of the end walls at said seats and in overlapping relation to the adjacent ends of the longitudinal strips and their opposite ends extended upwardly and inwardly and secured to the upper edges of the end walls in overlapping relation to the adjacent partitions to hold the grill in contact with said longitudinal strips.
4. A bottle carrying box comprising a body portion including side and end walls, the lower edges of the end walls at the confronting faces thereof being rabbeted to form seats of approximately one-half the width of the end walls and extending the entire length thereof, longitudinal strips constituting the bottom of the box and spaced apart to form ventilating openings, the opposite ends of the strips being fitted in said seats with the lower surfaces of the strips disposed flush with the lower edges of said side and end walls, reinforcing straps fitted around the end walls and extended over in overlapping relation to and bearing against the ends of the longitudinal strips at said seats with their opposite ends extended over the upper edges of said end walls, and fastening devices extending through the straps and engaging the ends of the strips at said seats.

EDWARD W. HUTCHINGS.
